CLAIM

The ornamental design for an utility shed, as shown and described.

DESCRIPTION

FIG. 1 is a top right front perspective view of an utility shed showing my new design;
FIG. 2 is a top plan view thereof;
FIG. 3 is a front elevational view thereof;
FIG. 4 is a right side elevational view thereof; the left side elevational view being a mirror image;
FIG. 5 is a rear elevational view thereof; and,
FIG. 6 is a bottom plan view thereof.
The broken line showing of environment in FIG. 6 is for illustrative purposes only and forms no part of the claimed design.
